US00D870080S

(12) **United States Design Patent** (10) **Patent No.:** **US D870,080 S**
(45) **Date of Patent:** **** Dec. 17, 2019**

(54) **WIRELESS HEADSET**

(71) Applicant: **GN AUDIO A/S**, Ballerup (DK)

(72) Inventor: **Bill Zeng**, Xiamen (CN)

(73) Assignee: **GN AUDIO A/S** (DK)

(**) Term: **15 Years**

(21) Appl. No.: **29/611,094**

(22) Filed: **Jul. 18, 2017**

(30) **Foreign Application Priority Data**

Feb. 1, 2017 (EM) 003734078-0001

(51) **LOC (12) Cl.** **14-01**

(52) **U.S. Cl.**

USPC **D14/223**; D14/205

(58) **Field of Classification Search**

(57) **CLAIM**

The ornamental design for a wireless headset, as shown and described.

DESCRIPTION

FIG. 1 is a perspective view of a wireless headset showing the new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top planar view thereof; and,

FIG. 7 is a bottom planar view thereof.

The broken lines shown in the drawings depict portions of the wireless headset that form no part of the claimed design.

1 Claim, 5 Drawing Sheets
